UNITED STATES PATENT OFFICE.

FERDINAND CHOP, OF HARTFORD, WISCONSIN.

AUTOMOBILE-HOOD.

1,198,189.

Specification of Letters Patent. Patented Sept. 12, 1916.

Application filed January 22, 1916. Serial No. 72,583.

To all whom it may concern:

Be it known that I, FERDINAND CHOP, a citizen of the United States, and a resident of Hartford, county of Washington, and State of Wisconsin, have invented certain new and useful Improvements in Automobile-Hoods, of which the following is a specification.

My invention relates to improvements in automobile hoods, and has for its object the production of a hood of this character which will be of improved construction, one which may be readily and easily removed when desired, but which, when in closed position, will be securely locked to the vehicle, and further one which will be highly efficient in use.

Other objects will appear hereinafter.

With these objects in view, the invention consists in the combinations and arrangements of parts hereinafter described and claimed.

The invention will be best understood by reference to the accompanying drawings forming a part of this specification, and in which,

Figure 1 is a central vertical longitudinal section of a hood embodying the invention, adjacent portions of an automobile being also shown, Fig. 2 is a top plan view of the device partly in section, Fig. 3 is a front elevation of Fig. 1, and Fig. 4 is a vertical transverse section of the construction.

The preferred form of construction, as illustrated in the drawings, comprises a hood adapted for arrangement between the stationary vertically disposed portions 1 and 2 of the vehicle between which the motor of the vehicle is arranged, the member 1 being the radiator which co-operates with the motor. Said hood comprises top sections 3 which are pivotally or hingedly connected at 4 so as to permit of free relative vertical movement of said sections.

Side sections 5 are pivotally or foldably connected with the outer or lower edges of the sections 3 as at 6, the construction thus far described being old and well known.

Provided at the under side of each section 3 adjacent the hinge 4 are depending curved keepers or hooks 7 adapted, when the sections 3 are in lowered position to embrace or engage under a stationary rod 8 which is rigidly supported at its ends in members 1 and 2. The arrangement is such, as will be seen, that upon upward swinging of the sec-

tions 3 to their upper limits of movement, the keepers 7 will be moved outwardly out of engagement with the rod 8 so that when said sections reach their upper limits of movement the same will be unlocked from the rod 8 so as to permit of removal of the hood. The arrangement is such then, as will be seen, that the hood sections 3 will be securely locked to the rod 8 only when said sections are in lowered position, each section being entirely independent of the other so that when but one section is rocked upwardly to open position carrying the keepers 7 thereof to releasing position, the other section will remain in lowered position with its keepers 7 in locking engagement with rod 8.

When the keepers 7 are in engagement with the rod 8, as clearly shown in Fig. 4, the rearward edges thereof engage against stationary stop fingers 9 which project from plates 9 rigidly fastened to flanges 10, the latter projecting inwardly from the members 1 and 2. Said stop fingers serve to prevent lateral movement of the keepers from engagement with the anchoring rod 8, it being clear that with this arrangement, when said keepers are in operative relation with said anchoring rod, the same, in being locked against lateral movement, will in turn serve to hold the hood against such movement.

Provided at the inner sides of side sections 5 at the ends thereof and adjacent the lower edges of said sections are channel engaging members 11 having shanks or stems 12 which are fastened to said sections by means of straps 13. The members 11 slidably engage with the flanges 10 and thus serve as a means of guiding the lower edges of sections 5 in the vertical movement of the same during vertical swinging of the top sections 3.

The sections of the hood at opposite sides of the latter are releasably supported in elevated positions by means of dogs 14 which are pivotally mounted at 15 upon plates 16 which are securely fastened upon the vehicle member 2. A helical tension spring 17 engaging at its lower end with each dog 14 and at its upper end with an inwardly projecting pin 18 serves to yieldingly hold the dog at its upper limit of movement. The arrangement is such that when either side of the hood is moved upwardly or opened, the corresponding dog 14 will automatically en-

gage with the lower edge of the corresponding section 5, as the latter reaches its upper limit of movement, and thus serve as a means of supporting the hood sections in elevated or open position. When it is desired to lower the hood section 5 to closed position it is only necessary to rock the engaging dog 14 downwardly to releasing position. The pins 18, as will be seen, in addition to serving as a means of connection for the springs 17 serve also as a means of limiting upward movement of the dogs 14.

The conventional hood fastening devices 19 are shown for coöperation with the side sections of the hood, being adapted for releasable engagement with loops 20 provided upon said sections. Handles 21 are also shown upon sections 5 at the outer sides thereof. Elongated vertically extending shields 22 are arranged along the lower edges of the hood sections 5, when the latter are in lowered position, which serve to form a sort of lap joint which is, of course, adapted to effectually exclude the weather.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention what I claim as new and desire to secure by Letters Patent is:

1. An automobile hood comprising, in combination, two top sections pivotally connected for relative upward swinging; and means in the upper part of the hood for engagement with the stationary part of the vehicle and acting as a supplemental means for automatically locking the hood against movement with respect to the vehicle when said sections are in lowered position, substantially as described.

2. An automobile hood comprising, in combination, two top sections pivotally connected together for relative upward swinging; and means in the upper part of the hood coöperating with each of said sections and acting as a supplemental means for automatically locking the hood against movement with respect to the vehicle when said sections are in lowered position, substantially as described.

3. An automobile hood comprising, in combination, two top sections pivotally connected together for relative upward swinging; a stationary anchoring element on the vehicle; and means carried by each of said sections at the upper portion thereof adapted for engagement with said anchoring element to act as a supplemental means for au-

tomatically locking the hood against movement with respect to the vehicle when said sections are in lowered position, substantially as described.

4. An automobile hood comprising, in combination, two sections pivotally connected together for relative upward swinging; a stationary anchoring element on the vehicle; and curved keepers carried by said sections adapted for engagement with said anchoring element to act as a supplemental means for locking the hood against movement with respect to the vehicle when said sections are in lowered position, substantially as described.

5. An automobile hood comprising, in combination, two top sections pivotally connected together for free upward swinging; a stationary rod supported by said vehicle within said hood; and means carried by said sections adapted for engagement with said rod to lock the hood thereto only when said sections are in lowered position, substantially as described.

6. An automobile hood comprising, in combination, two top sections pivotally connected together for free upward swinging; a stationary rod supported by said vehicle within said hood; and hook members on each of said sections adapted for independent engagement with said rod only when said sections are in lowered position to lock the hood thereto, substantially as described.

7. An automobile hood comprising, in combination, two top sections pivotally connected together for free upward swinging; a stationary rod supported by said vehicle within said hood; means carried by said sections adapted for engagement with said rod to lock the hood thereto against upward movement only when said sections are in lowered position; and means adapted, when said sections are in lowered position, to lock said hood against lateral movement, substantially as described.

8. An automobile hood comprising, in combination, two top sections pivotally connected together for free upward swinging; a stationary rod supported by said vehicle within said hood; hook members on each of said sections adapted for independent engagement with said rod only when said sections are in lowered position to lock the hood thereto against upward movement; and means adapted for coöperation with said hook members for locking said hood against lateral movement, when said sections are in lowered position, substantially as described.

9. An automobile hood comprising, in combination, two top sections pivotally connected together for free upward swinging; a stationary anchoring element supported by said vehicle within said hood; hook members carried by said sections adapted for engage-

ment with said anchoring element, only when said sections are in lowered position, to lock the hood thereto against upward movement; and stationary stops for engagement with the rearward sides of said hook members for locking said hood against lateral movement when said sections are in lowered position, substantially as described.

10. An automobile hood comprising in combination, two top sections pivotally connected together for free upward swinging; side sections foldably connected with said top sections; and means for guiding said side sections to and from folded positions during swinging movement of said top sections, substantially as described.

11. An automobile hood comprising, in combination, two top sections pivotally connected together for free upward swinging; side sections foldably connected with said top sections; inwardly extending flanges on the vehicle at the ends of the hood; and means on said lower sections slidably engaging with said flanges whereby said sections are guided in the folding movement of the same during swinging of said top sections, substantially as described.

12. An automobile hood comprising, in combination, two top sections pivotally connected together for free upward swinging; side sections foldably connected with said top sections; inwardly extending flanges on the vehicle at the ends of the hood; and channel formed members on said side sections slidably engaging with said flanges whereby said sections are guided in the folding movement of the same during vertical swinging of said top sections, substantially as described.

13. An automobile hood, comprising, in combination, two top sections pivotally connected together for free upward swinging; side sections foldably connected with said top sections; means for guiding said side sections in the folding movement of the same during swinging movement of said top sections; and means for locking said sections at their upper limits of movement, substantially as described.

14. An automobile hood comprising, in combination, two top sections pivotally connected together for free upward swinging; side sections foldably connected with said top sections; means for guiding said side sections in the folding movement of the same during swinging movement of said top sections; and means adapted for engagement with the lower edges of said side sections for supporting the same in elevated position, substantially as described.

15. An automobile hood comprising, in combination, two top sections pivotally connected together for free upward swinging; side sections foldably connected with said top sections; means for guiding said side sections in the folding movement of the same during swinging movement of said top sections; and spring controlled dogs adapted, upon upward movement of said sections, to automatically engage with the lower edges of said side sections to hold the same in elevated positions, substantially as described.

16. An automobile hood comprising, in combination, two top sections pivotally connected together for free upward swinging; side sections swingingly connected with the outer edges of said top sections; and means provided in the hood for releasably supporting said sections in elevated position, substantially as described.

17. An automobile hood comprising, in combination, two top sections pivotally connected together for free upward swinging; side sections swingingly connected with the outer edges of said top sections; and spring controlled dogs adapted for releasable engagement with the lower edges of said side sections for supporting said sections in elevated position, substantially as described.

In testimony whereof I have signed my name to this specification in the presence of two subscribing witnesses.

FERDINAND CHOP.
